CONTAINER FILLING MACHINE WITH MEANS TO CONTROL THE LEVEL OF FILL

Carl L. Day and Rudolph H. Breeback, Baltimore, Md., assignors to Crown Cork & Seal Company, Inc., Baltimore, Md., a corporation of New York

Application June 11, 1952, Serial No. 292,882

20 Claims. (Cl. 141—234)

The present invention relates to container filling machines.

In the filling of containers with carbonated liquids, including beer, it is desirable to so handle the filling operation that the height of filling can be accurately and uniformly controlled. It heretofore has been proposed to control the height of the filling by means of a ball float adapted to be closed by rising liquid. However, it has been found that some types of foam, especially beer foam, may lift the float to closed position, with the result that the actual height of the liquid has little control upon the ball float.

An object of the present invention is to provide a filling head wherein the height of filling will be determined only by the actual height of the liquid in the container.

It frequently is desirable to also include a float valve in the venting passage to thereby assure that no excessive amount of liquid and foam can rise in the venting passage to interfere with the filling of the next container placed under the filling head. The invention contemplates use of a float valve adapted to be closed by an excessive rise of liquid, the float valve being positioned above the filling height control.

Another object of the invention is to provide a means to control the height of filling and which means is readily adjustable to vary the height of filling.

In the embodiment of the invention disclosed herein, the height controlling means comprises a collar forming the lower end of the vent passage through which air and gas in the container are vented from the container during the inflow of liquid. By having the collar threaded to the underside of the filling head, its vertical position with respect to the filling head readily can be adjusted to control the height of filling to a very accurate degree.

Another object of the invention is to provide means whereby the height of filling can be controlled by adjustment of the vertical position of the container with respect to the filling head.

It heretofore has been common practice to lift containers into sealed engagement with a filling head so that the filling operation can be performed while the container is sealed to the filling head. We have discovered that by providing a compressible member to engage the container and adjusting the lifting movement of the container, the height of filling readily can be controlled. For example, if the lifting of the container is performed by a vertically reciprocable container supporting platform lifted by fluid pressure, a slight increase in the lifting pressure to thereby cause the container to be positioned higher with respect to the vent control means will cause the height of filling to be slightly reduced.

Other objects and advantages of the invention will be apparent from the following specification and accompanying drawings.

In the drawings,

Figure 1 is a front elevation of a filling head of the present invention and showing a can supported on a con-

2

tainer supporting platform in alignment with the filling head.

Figure 2 is a vertical section through the filling head of Figure 1, the view showing the flow passages aligned for filling.

Figure 3 is a vertical sectional view through the lower portion of the filling head showing a can initially engaged with the gasket of the head.

Figure 4 is a fragmentary view similar to Figure 3 and showing the can further lifted.

Figure 5 is an exploded view showing a fragment of the filling head together with parts forming the height control means, and

Figure 6 is a fragmentary view in axial section of a filling table and showing means for controlling the lifting of the container supporting platforms.

The filling head of the present invention includes a body 10 having a gasket 12 inserted in its outer circular face so that the outer surface 14 of the gasket thereby forms the seat face of the body 10. The body 10 will be secured to the periphery of the reservoir carrying superstructure of a filling machine in a manner such as described in the application of Rudolph H. Breeback for Filling Head, Serial No. 213,950, filed March 5, 1951.

The disc-type valve 16 of the filling head is rotatable upon a stud 18 projecting centrally from the seat face 14. In accordance with usual practice, the body 10 and disc valve 16 will be provided with flow passages adapted to be aligned or non-aligned by movement of the disc valve 16 through the several positions indicated in dotted lines in Figure 1 to first establish counterpressure in a container to be filled, then cause liquid to flow into the container while the air and gas in the container is delivered to the upper portion of the filling reservoir, and thereafter close the passages. Then the container will be lowered from the filling head, and the disc valve 16 may be moved to counterpressure position to cause gas to flow from the reservoir through the venting passages to thereby clear those passages of any foam or liquid before another container is moved upwardly into engagement with the filling head.

Each filling head of the machine will have a container supporting platform 20 in alignment therewith, the container supporting platforms being vertically reciprocable in the filling table 22 to thereby raise and lower containers, such as the illustrated can C, with respect to the filling head. As is described in Robert J. Stewart et al. Patent No. 2,202,033, issued May 28, 1940, the container supporting platforms may be moved downwardly by a cam such as 24 (Figure 6) fixed in the path of rotation of the filling table 22, the platforms being raised by the action of compressed air or other fluid. In more detail, as is illustrated in Figure 6, and as is described in said Stewart et al. patent, each filling platform 20 is mounted on the upper end of a cylinder 28 which is vertically reciprocable upon tube 30 extending upwardly from a circular manifold 32 secured to the rotatable filling table. A source of compressed air such as the tank 34 may be secured beneath the filling table 22 to rotate with the latter, and tank 34 is connected to manifold 32 by a tube 36 which is so curved upwardly that it will clear the cam 24 during rotation with table 22. As also is described in said Stewart et al. patent, during the time that a container supporting platform 20 is adjacent the front or fixed work table of the machine, the roller 26 carried on the cylinder of that platform will be in engagement with the lower surface of the cam 24 so that the platform 20 thereby will be lowered to have a filled can removed therefrom and an empty can placed thereon. Thereafter, as the table 20 continues to rotate, roller 26 will move out of engagement with cam 24 so that the pressure in the manifold 32 and tubes 30 quickly will raise platform

20 through the positions illustrated in Figures 1, 2 and 3 so that the mouth of the can will be brought into sealed engagement with the filling head as indicated in Figure 4 so that the filling cycle may begin.

As will be clear from the above, the body 19 of the filling head of the present invention includes a liquid passage 40 opening to its seat face and connected by a pipe 42 to the liquid containing portion of the filling reservoir. Another and right-angled passage 44 extends from the seat face 14 downwardly through an aligned passage 46 in the can adapter 48 secured to the lower portion of the body 10 by a collar 50. Passage 46 has a filling nozzle 52 threaded therein. It will be observed that the filling head under discussion differs from that of said Breeback application in that the present filling head has the passage 46 slightly forward of the central axis of the depending portion 47 of the body 10. Also, the present head 10 includes a can engaging adapter 48. Features of the can adapter 48 are particularly involved in the present invention.

The liquid passages 40 and 44 are adapted to be aligned during the filling stage by a passage 54 in the disc valve element 16.

The filling head body 10 also includes a gas passage 56 opening to its seat face 15 and communicating with a pipe 58 leading to the upper and gas containing portion of the reservoir. The numeral 60 designates a right angled gas passage leading from the seat face 14 to an aligned passage 62 in the adapter 48 and which opens to a float chamber 64 as hereinafter described. During the filling stage of the filling cycle, the passages 56 and 60 will be placed in communication with each other by a passage 66 in the disc valve 16. Because the liquid flow passages will at that moment be bridged by the disc valve passage 54, beer or other liquid being filled in the containers will flow through the liquid passages and into the can from nozzle 52 while the air and counterpressure gas in the can will be returned to the upper portion of the filling reservoir through the passages 60, 66, 56, and pipe 58. It will be understood that in accordance with usual practice, the filling head may include other gas passages through which counterpressure flow into the container will occur and that, during counterpressure, the liquid flow passages will be closed.

As is described in said Breeback application, disc valve 16 will be rotated to the above-mentioned flow positions by trips spaced about the path of rotary travel of filling table 22, the trips engaging the arms 16a and 16b of the valve.

Referring now to the can adapter 48, this is of sufficient overall diameter to receive the open mouth M of a flat topped can C. Adapter 48 includes a relatively resilient and compressible sealing ring or gasket 70 of sufficient diameter to engage the upper edge or flange M of the can C. Gasket 70 is held in position upon the adapter 48 by means of a sleeve 72 secured to the adapter 48 by means of machine screws 74 extending downwardly through enlarged bosses on the adapter 48 and into the threaded sockets of corresponding enlargements 76 of sleeve 72. The gasket 70 includes a flange at its upper end adapted to rest upon an inwardly extending flange or shoulder 78 provided immediately below the upper end of sleeve 72. As is disclosed in Bondurant Patent No. 2,082,534, issued June 1, 1937, the inner surface of sleeve 72 may be cut away to normally provide a space 80 into which gasket 70 may protrude when the gasket is pressed upwardly by a can.

It will be observed that the inner, lower surface 82 of sleeve 72 flares outwardly to tend to guide the mouth M of a can into alignment with the lower end of gasket 70 and that the lower end of gasket 70 normally will be slightly above the upper end of the flared portion 82. Moreover, the outer portion 84 of the lower end of gasket 70 is inclined upwardly and outwardly at an angle such as indicated in the drawings to thereby assure that the

mouth M of a can will firmly contact with gasket 70 but without the possibility of the portion 84 of the gasket lying at too steep an angle with respect to the mouth of the can.

5 Gasket 70 lies outwardly of a depending circular flange 86 formed integrally with adapter 48, flange 86 terminating at the lower end of gasket 70. Flange 86 defines a circular space 88 in the lower surface of adapter 48, the upper end of the space being defined by a horizontal 10 wall 90. Space 88 forms a relatively large area to accommodate foam upon the surface of the beer and also to cooperate with the can C to create a headspace area as hereinafter described.

As is best illustrated in Figures 2 and 5, the recess 64 15 of adapter 48 to which gas passage 62 opens is of cylindrical form and extends upwardly from the wall 90. The top wall of recess 64 is curved and a sleeve 91 is fitted in an enlargement of passage 62 which opens directly to the upper central portion of recess 64. As 20 shown in Figure 5, the lower end of sleeve 91 is beveled to form a valve seat. A cage 94 including downwardly and inwardly projecting ribs 96 is fitted in recess 64 to support a ball float valve 98. A collar 100 including an inwardly tapered surface engages the lower portion of the ribs 96 to thereby hold them in proper position and restrict the lower end of the ball float containing area or recess 64. Collar 100 is welded in the lower end of recess 64 and has a vent controlling collar or nipple 102 threaded therein, the central bore 103 of collar 102 being 30 of relatively reduced diameter, for example, about $\frac{1}{8}$ of an inch. It will be observed from Figure 2 that the lower end of collar 102 is positioned substantially flush with the lower end of the flange 86. As is herein- 35 after described, the position of collar 102 may be adjusted to thereby control the height of filling.

In the operation of the structure described above, and 40 particularly the adapter 48, when a can C is moved upwardly by a filling platform 20, the mouth M of the can will enter sleeve 72 to initially come into engagement with gasket 70 as indicated in Figure 3. As the lifting of the platform 20 continues, the can will reach a 45 position relative to the gasket such as indicated in solid lines in Figure 4. Because the gasket 70 is resilient and highly compressible, the upward movement of the can will cause the gasket to expand laterally into the space 80 in collar 82. The can will now be in fully sealed relation with respect to the filling head. Immediately thereafter, by the usual operation of the filling machine, valve 16 will be rotated from "Neutral stage" Figure 1 50 to "Counterpressure stage" so that counterpressure will flow into the can through the passage 62 of the adapter and past the then lowered ball 98 and through collar 102. If desired, other counterpressure flow passages also 55 may be provided. Then the disc valve 16 will be moved to "Filling stage" wherein passages will be aligned as indicated in Figure 2 so that the liquid will flow into the can through the nozzle 52 while the air and gas in the can will vent to the upper portion of the filling reservoir through collar 102, between the ribs 96 of cage 94, and 60 past ball 98 to the reservoir.

As the beer and any surplus foam rise in the can, the 65 foam may accumulate in the space 88 and some foam may move upwardly in the vent collar 102 into recess 64. However, because ball 98 is above the restricted collar 102, it will not readily be accessible to foam. When 70 the level of the beer rises to the lower end of the venting collar 102, beer no longer can rise in the can though it can move up into collar 102. However, the trip to operate the disc valve 16 back to "Neutral stage" will be so positioned that at this moment, or an instant thereafter, valve 16 will be moved to close both the liquid and gas passages so that no further beer will flow into the can. If any beer has moved upwardly in the bore 103 of collar 102, such beer may move downwardly into the 75 can when the can is subsequently lowered. Because of

the small size of the bore 103, such beer will not result in overfilling to any substantial extent.

As is explained in said Bondurant patent, the can will lower to a marked extent from the sealed position indicated in solid lines in Figure 4, for example, by a distance of about $\frac{1}{8}$ to $\frac{3}{16}$ of an inch, before the mouth M of the can moves out of sealed relation with the gasket 70. Therefore, before the can breaks away from the gasket, the headspace above the surface of the liquid in the can and including the space 88 in adapter 48 will enlarge in volume to thereby reduce the pressure within the headspace. This reduction in pressure will lower the headspace pressure to a point more closely approximating the atmospheric pressure existing exteriorly of the can. As a result, when the can finally breaks away from the gasket 70, the beer will not tend to agitate and foam.

In the event that beer moves upwardly through bore 103 of collar 102 sufficiently high to lift float valve 98 into engagement with collar 91, the escape of gas from the can will be completely cut off so that no further liquid can flow downwardly through nozzle 52. Because only a very limited quantity of beer can be received in recess 64 before float valve 98 closes, any beer which moves downwardly from recess 64 through collar 102 when the can is lowered will not markedly overfill the can.

Because collar 102 only can be sealed by actual liquid, it serves as a highly satisfactory means for determining the height of filling of each can. Also, if it is desired to vary the height of filling, the collar 102 may have a gasket or washer 108 of different thickness fitted thereabout to engage the sleeve 100 to thereby adjust the height of filling. If desired, the position of the collar 102 can be changed by simply rotating it to change its threaded relation with collar 100.

Another system of controlling the height of filling made practicable by the present invention is that of changing the pressure of compressed air or other fluid in the platform lifting manifold 32. For example, if when a pressure of thirty-five pounds per square inch is maintained in the manifold 32, a can C compresses the gasket 70 by $\frac{3}{16}$ of an inch, an increase of about five pounds per square inch in manifold 32 will raise the can an additional $\frac{1}{16}$ of an inch, as indicated in dotted lines in Figure 4, thereby lowering the filling level in the can by $\frac{1}{16}$ of an inch. Correspondingly, by reducing the pressure in manifold 32, the height of filling can be increased. As is illustrated in Figure 6, the line 36 leading from tank 34 to manifold 32 may be provided with a gauge 106 whereby the pressure charged into the line 36 through valve 108 may be determined to thereby control the filling height. It will be understood that instead of tank 34, line 36 may be connected through a suitable fitting to a compressed air line leading from the machine through the central stationary post.

It will be noted filling nozzle 52, in addition to its function of delivering beer to container C, also serves as a displacement member. As a displacement member, the filling nozzle 52 determines to a limited extent the height of fill of the container when the vertical position of the container is changed relative to its sealing engagement with the filling head. The position of the vent collar 102 with respect to the lip of the container, as mentioned heretofore, controls the height of fill and it may be varied by use of the washer 108 or by changing the vertical movement of the platform lift 20 so that the container compresses to a greater or lesser extent the gasket 70. In the latter instance, nozzle 52 extends into container C a greater or lesser distance depending on the compression of gasket 70. If nozzle 52 extends into container C a greater distance, the displacement will be greater and the height of fill will be less. On the other hand, if nozzle 52 extends into the container a

lesser distance, the displacement will be less and the height of fill greater.

The terminology used in the specification is for the purpose of description and not of limitation, the scope 5 of the invention being indicated in the following claims.

We claim:

1. In a container filling machine, a filling head element, a container supporting element, said filling head element including a liquid flow nozzle and a container venting means arranged to be closed by rise of liquid in the container, one of said elements including a container engaging member capable of compression within a substantial range, vertically movable means to move said container supporting element vertically toward said filling head element, and means to control the vertical travel of said last-named means to thereby vary the compression of said member within said range and the height of filling of the container.
2. A container filling machine of the character described in claim 1 wherein said compressible member is annular and carried on the filling head element to surround said liquid flow nozzle.
3. A container filling machine of the character described in claim 1 wherein said container supporting element moving means is fluid actuated and the pressure of the fluid is adjustable.
4. A container filling machine of the character described in claim 1 wherein said container venting means is vertically adjustable with respect to said filling head.
5. A container filling machine of the character described in claim 1 wherein said container venting means includes a float valve closed by rise of liquid.
6. In a filling head, a body including a valve seat and a downwardly extending portion provided with a horizontal face, a filling nozzle projecting downwardly from the horizontal face, said body being provided with a liquid flow passage extending from the valve seat to said nozzle, a container engaging gasket surrounding the horizontal face, said body being provided with a chamber opening upwardly from the horizontal face within said gasket, a gas flow passage extending from the chamber to the valve seat, said body including a pair of passages extending from the valve seat and adapted to be connected respectively to a source of liquid and a source of gas,
- 35 7. A container filling machine of the character described in claim 6 wherein said body is rotatable on the valve seat to connect said liquid and gas flow passages respectively to the passages of said pair, a float valve in the chamber, and a collar defining the lower end of the chamber, said collar being provided with a restricted bore and extending downwardly from the horizontal face of said body.
- 40 8. A container filling machine of the character described in claim 6 wherein said collar has its lower end lying in a horizontal plane.
- 45 9. In a rotary filling machine, a group of filling elements, a group of container supporting elements, each of said filling elements including a liquid flow nozzle and a container venting means arranged to be closed by rise of liquid in a container associated therewith, each of the elements of one of said groups of elements including a container engaging member capable of compression within a substantial range, vertically movable means to move said container supporting means toward said filling head elements, and means to simultaneously control the vertical movement of all said container supporting elements to thereby vary the compression of said bodily compressible members within said range and the height of filling of containers.
- 50 10. A container filling machine of the character described in claim 9 wherein said compressible member is annular and carried on the filling head element to surround said liquid flow nozzle.
- 55 11. A container filling machine of the character de-

scribed in claim 9 wherein said container supporting element moving means is fluid actuated and the pressure of the fluid is adjustable.

12. A container filling machine of the character described in claim 9 wherein said container venting means is vertically adjustable with respect to said filling head.

13. A container filling machine of the character described in claim 9 wherein said container venting means includes a float valve closed by rise of liquid.

14. In a container filling machine, a filling head, said filling head including a valve seat and a downwardly extending portion provided with a horizontal face, a filling nozzle projecting downwardly from the horizontal face, said body being provided with a liquid flow passage extending from the valve seat to said nozzle, a container 15 engaging gasket surrounding the horizontal face, said container engaging gasket being capable of compression within a substantial range, said body being provided with a chamber opening upwardly from the horizontal face within said gasket, a gas flow passage extending from the chamber to the valve seat, said body including a pair of passages extending from the valve seat and adapted to be connected respectively to a source of liquid and a source of gas, a valve rotatable on the valve seat to connect said liquid and gas flow passages respectively to the passages of said pair, a float valve in the chamber, a collar defining the lower end of the chamber, said collar being provided with a restricted bore and extending downwardly from the horizontal face of said body, and a container supporting platform, means to move said container supporting platform toward said filling head element, and means to control the vertical travel of said last mentioned means to thereby vary the compression of said compressible gasket within said range and the height of filling of the container.

15. A container filling machine of the character described in claim 14 wherein said container supporting platform moving means is fluid actuated and the pressure of the fluid is adjustable.

16. A container filling machine of the character described in claim 14 wherein said collar has its lower end lying in a horizontal plane and wherein said collar is vertically adjustable with respect to the body of said filling head.

17. In a container filling machine, a filling head element, a container supporting element, said filling head element including a liquid flow nozzle and a container venting means arranged to be closed by the rise of liquid in the container, one of said elements including a member having a container engaging sealing face, said sealing face being capable of vertical movement over a substantial range with respect to said venting means, means

to move said container supporting element vertically toward said filling head element, and means to control the vertical travel of said last named means to thereby vary the movement of the sealing face of said member with respect to said venting means within said range and the height of filling of the container.

18. A container filling machine of the character described in claim 17, wherein said container supporting element moving means is fluid-actuated and wherein said control means is a valve to vary pressure of fluid actuating said container supporting platform.

19. In a container filling machine, a filling head element, a container supporting element, said filling head element including a liquid flow nozzle and a container venting means arranged to be closed by the rise of liquid in the container, said filling head element also including a member having a container engaging sealing face, said sealing face being capable of being moved over a substantial vertical range with respect to said venting means, 20 means to move one of said elements with respect to the other to thereby place a container in sealing engagement with said sealing face, and means to control the movement of said last named means to thereby vary the movement of the sealing face of said member with respect to said venting means within said range and the height of filling of the container.

20. In a container filling machine, a filling head element, a container supporting element, said filling head element including a liquid flow nozzle and a means the projection of which into said container determines the height of fill, said filling head element also including a member having a container engaging sealing face, said sealing face being capable of being moved over a substantial vertical range with respect to said means projecting into said container, means to move one of said elements with respect to the other to thereby place a container in sealing engagement with said sealing face, and means to control the movement of said last named means to thereby vary the movement of the sealing face of said member with respect to said means projecting into said container within said range and the height of filling of the container.
